Inventor
Charles G. Dyott
By his Atty.

UNITED STATES PATENT OFFICE.

CHARLES G. DYOTT, OF PHILADELPHIA, PENNSYLVANIA, ASSIGNOR TO THE PENNSYLVANIA GLOBE GAS LIGHT COMPANY, OF SAME PLACE.

LAMP OR LANTERN.

SPECIFICATION forming part of Letters Patent No. 374,144, dated November 29, 1887.

Application filed February 10, 1886. Serial No. 191,438. (No model.)

To all whom it may concern:

Be it known that I, CHARLES G. DYOTT, of the city and county of Philadelphia, and State of Pennsylvania, have invented an Improvement in Lamps and Lanterns, of which the following is a specification.

My invention has reference to lamps and lanterns; and it consists in certain improvements, fully set forth in the following specification and shown in the accompanying drawing, which forms part thereof.

In a patent granted to me September 22, 1885, and numbered 326,550, is set forth a construction of lamp for using vaporized hydrocarbon fluid as a source of light, and said hydrocarbon-burner is combined with a device by which part of the products of combustion are returned to the lower part of the lamp and commingled or mixed with the incoming fresh air to impart caloric thereto. This invention is essentially an improvement upon what is shown in said Letters Patent, and has particular reference to that class of lamps. Many parts of the invention are equally adapted to other forms of lamp, such as those of Siemens, Hoofman, Lipsey, Schulke, Sanderson, &c., and therefore I do not in any wise limit myself to any particular form.

My improvements consist, chiefly, in a more efficient arrangement of the parts of the lamp to insure greater steadiness and brilliancy of the flame and means for regulating the supply of oil to the burner, as well as certain other improvements, which will be more fully understood by a reference to the drawing and claims.

In the drawing is shown a sectional elevation of a hydrocarbon lamp or lantern embodying my improvements.

A is the lower chamber, and B is the upper chamber, the two being connected by the return-flues C, whose function is to return the hot products of combustion, or that part caught by the vessel D, located in the chamber B and provided with the contracted or funnel-shaped orifice d, to increase the draft upon the ascending products and force them down the tubes C, from which they emerge into the bottom of the chamber A, preferably between the screens T T, and are mixed with the ascending fresh air.

E is the globe, which is supported upon chamber A and located between it and the adjustable section I of the chamber B, which adjustable section is provided with a cap, G, having 55 the downwardly-projecting tubular shield g, to hide the upper or ragged portion of the flame.

J is a tube extending upward from the cap G and formed as a continuation of the shield-section g, and, being of preferably smaller diameter than the mouth of the receptacle D, directs the products of combustion therein. The globe does not come into direct contact with the cap G, but is preferably held away from it by a screen, H, or projections, or any 65 device whereby a current of cold air may pass over it, as indicated by the arrows, to keep the glass more or less cool and prevent it from melting and being pressed down by the weight of the cap and its tubes. By lifting the cap 70 the globe may be removed.

K is the Argand burner, which consists of an annular chamber with a number of vertical tubes or burners, and is located between the deflector F of the case or chamber A and the 75 vapor-chamber L. The top of the vapor-chamber L is provided with the vaporizer M, and consists of a solid metallic head having lateral passages N and an oil-aperture, m, adapted to be closed or opened by the needle-valve R, 80 which extends down through the oil-supply pipe Q, connected with the vaporizer M, as shown, and brought to the outside of the lamp, where it may be operated to control or regulate the flow of oil through the aperture m. 85 The valve-rod of this needle-valve is provided with a screw-section, r, whereby by turning it a longitudinal movement may be imparted.

Extending upwardly above the vaporizer and carried thereon is the heat-conductor O, 90 which may be made like a tube or any other shape desired. This conductor extends up into the tubular shield g, and is heated by the escaping products of combustion, and in turn conducts its heat down to the vaporizer M, 95 and even to the tube Q. It also heats the vapor-chamber L, and thereby keeps the vapor from condensing when once it is formed. The vaporized oil passes into the vapor-chamber at the top and descends to the burner. It is 100 preferably caused to pass through one or more screens, l, to thoroughly mix and equalize its

distribution, whereby all flickering or jumping at the burner is obviated.

P is a deflector of refractory material, which is used to deflect the flame, throwing it somewhat outward, and, being made of a light or white material, it acts as a reflector, increasing the brilliancy of the flame and the candle-power of the lamp. This deflector P is made cylindrical or cup-shaped, and extends around the vaporizer and vapor-chamber, and is supported upon the latter. It preferably does not touch the vaporizer or upper part of the vapor-chamber, but forms an annular dead-air space around them, preventing changes in their temperature, which would take place if not thus surrounded and protected from draft. There being more air-space between the burner K and deflector F than between it and the vapor-chamber L, I provide the annular disk or screen U, arranged upon the outside only of the burner, as shown, leaving an open annular space, u, for free passage of air; or, if desired, the screen U may be open-meshed and extend to the case or chamber A. This will insure as much air passing upon the inside of the burner-tubes as upon the outside of them, and will cause a uniform flame and one in which the carbonaceous products are fully consumed.

W is an auxiliary valve-body which receives oil from the vertical oil-tube Q.

X is a valve working in the valve-body W, which extends outside of the case or chamber A, and is used to supply oil to the lighting-cup S, located below the oil-outlet s from the valve-body and surrounding the oil-tube Q, and to which said tube is attached. This lighting-cup is supported by a frame riveted to the chamber A, and through its mediation the vaporizer, conductor, vapor-chamber, and burner are sustained in position within the lamp.

Y is a covered passage-way or door placed in the casing A, and in such a position that the lighting-cup may be reached through it with a lighted match to taper when starting the lamp. The valve R being closed and valve X being opened, oil will pass from pipe V into vertical pipe Q and out through passage s into the lighting-cup S. The valve X is then shut off and the oil in the cup ignited. The flame of the burning oil surrounds the vertical oil-pipe Q and envelops the Argand burner, and the vapor-chamber and these parts by conduction heat the vaporizer. Oil is then admitted to the vaporizer by opening the valve R slightly, and the vapor passes through the chamber L to the burner K. During these operations air is supplied as the supporter of combustion in the manner hereinbefore specified—that is to say, up through the screens T in the lower chamber, A, and up to the burner. This air would be heated if the products of combustion were returned by pipes C. The burner-flame now passes upward around the deflector P and into the shield g, heating the conductor O, which in turn heats the vaporizer and keeps it hot and insures its action

without aid from the lighting-cup. The escaping products of combustion pass up through case B and directly into the atmosphere, or may be conveyed away by pipes, and that portion of the products collected by the vessel D passes back down the pipes C to the chamber or case A, and mixes with ascending air, imparting heat to it to furnish the lamp with a hot-air supply, as hereinbefore set out.

I do not limit myself to the particular details of construction shown, as it is evident that the parts may be modified in various ways without departing from my invention. For instance, the conductor O might be solid or given other shapes, and in place of the deflector P two disks, as indicated in dotted lines, might be used.

I am well aware that in heating-stoves using oil vapors it has been proposed to supply oil to the lighting-cup by a separate valve from that supplying oil to the burner; but beyond this similarity and the location of the lighting-cup under the generator there is practically no similarity with my invention. Such stoves are set out in Patents No. 270,587, of 1883, and No. 255,245, of 1882.

In 1885 a patent, No. 326,550, was granted to me for a gas-burning lamp, said patent also showing the application of oil as the illuminating agent, and this application is for an improvement upon said Letters Patent.

Having now described my invention, what I claim as new, and desire to secure by Letters Patent, is—

1. In a vapor-lamp, the combination of an oil vaporizer or generator, an Argand burner connecting therewith and located below it, and a deflector located above the burner and surrounding the said vaporizer, but of less diameter than the burner and located centrally therewith, substantially as and for the purpose specified.

2. In a vapor-lamp, the combination of an oil vaporizer or generator, an Argand burner connecting therewith and located below it, and a deflector located above the burner and surrounding the said vaporizer of greater diameter than the vaporizer to form a dead-air space between it and said vaporizer, but of less diameter than the burner and located centrally therewith, substantially as and for the purpose specified.

3. In a lamp, the combination of an oil vaporizer or generator, a burner connecting therewith and located below, and a deflector surrounding the said vaporizer or generator and within the burner, whereby it is interposed between the generator and the burner, and a heat-conductor extending above the deflector and connecting with the vaporizer, substantially as and for the purpose specified.

4. In a lamp, the vaporizer or generator, in combination with a vapor-burner located below and around the vaporizer, a ring or cylinder, substantially as set forth, to deflect the flame away from said vaporizer, and a heat-conductor extending upward from the vapor-

- izer and centrally located with respect to the burner, substantially as and for the purpose specified.
5. In a lamp, the vaporizer or generator, in combination with a vapor-burner located below and around the vaporizer, a ring or cylinder, substantially as set forth, to deflect the flame away from said vaporizer, and a heat-conductor extending upward from the vaporizer and centrally located with respect to the burner, and a depending shield to hide the upper or ragged portion of the flame and deflect the flame toward the central conductor, substantially as and for the purpose specified.
15. 6. In a lamp, the vaporizer or generator, in combination with a vapor-burner located below and around the vaporizer, a ring or cylinder, substantially as set forth, to deflect the flame away from said vaporizer, and a heat-conductor extending upward from the vaporizer and centrally located with respect to the burner, and a depending shield to hide the upper or ragged portion of the flame and deflect the flame toward the central conductor, a lower draft-chamber, an upper chamber carrying said shield, and a globe interposed between the said chambers and an air-passage between the upper part of the globe and chamber, substantially as and for the purpose specified.
25. 7. In a lamp, the vaporizer or generator, in combination with a vapor-burner located below and around the vaporizer, a ring or cylinder, substantially as set forth, to deflect the flame away from said vaporizer, and a heat-conductor extending upward from the vaporizer and centrally located with respect to the burner, and a depending shield to hide the upper or ragged portion of the flame and deflect the flame toward the central conductor, substantially as and for the purpose specified.
30. 8. In a lamp, the combination of a glass globe or chimney, an oil-vaporizer, a burner connecting therewith, a valve to supply oil to the burner or shut it off, a lighting-cup located below the burner and vaporizer, a second valve to supply oil to the said lighting-cup independently of the supply to the burner, and a case surrounding the oil-cup and burner and forming a draft-chamber with a covered passage in the side of said casing to admit a light for igniting the oil in the lighting-cup, substantially as set forth.
35. 9. In a lamp, the combination of an oil-vaporizer, a burner connecting therewith, a valve to supply oil to the burner or shut it off, lighting-cup located below the burner and vaporizer, a second valve to supply oil to the said cup independently of the supply to the burner, a casing surrounding the oil-cup and burner and forming a draft-chamber, and a covered passage in the side of said casing to admit a light for igniting the oil in the lighting-cup, substantially as and for the purpose specified.

In testimony of which invention I hereunto set my hand.

CHARLES G. DYOTT.
